PLASTIC PILE RUG

Beatrice Edesess, Brookline, Mass., assignor to American Biltrite Rubber Co., Inc., Chelsea, Mass., a corporation of Delaware

Filed Sept. 21, 1961, Ser. No. 66,790

Term of patent 14 years

(Cl. D92—21)

FIG. 1

FIG. 3

FIG. 1 is a plan view of a plastic pile rug, showing my new design,

FIG. 2 is a fragmentary view on an enlarged scale showing the fringe portion of the design, and

FIG. 3 is a sectional view on the line 3—3 of FIG. 2. The rug is molded in its entirety of plastic material.

I claim:

The ornamental design for a plastic pile rug, substantially as shown and described.
